UNITED STATES PATENT OFFICE.

HENRY BERRY, OF SHELTON, ASSIGNOR TO THE DERBY SILVER COMPANY,
OF DERBY, CONNECTICUT.

DESIGN FOR AN ORNAMENTAL COVERED RECEPTACLE.

SPECIFICATION forming part of Design No. 24,184, dated April 9, 1895.

Application filed March 8, 1895. Serial No. 541,050. Term of patent 7 years.

To all whom it may concern:

Be it known that I, HENRY BERRY, a citizen of the United States, residing at Shelton, in the township of Huntington, county of Fairfield, 5 and State of Connecticut, have invented and produced a new and original Design for an Ornamental Covered Receptacle, of which the following is a specification, reference being had to the accompanying drawing, forming a part thereof, and which illustrates, in a perspective view, an ornamental covered receptacle embodying my design, the cover or lid being shown tilted upward to more clearly disclose its outline.

15 The leading feature of my design consists in the ornamental form and configuration of the covered receptacle, substantially as shown in the accompanying drawing, in which it will be observed that the body of the receptacle is elongated horizontally and in its sphe-

roidal outline approximates that of an egg, and that the upper surface of the receptacle has a cover which closes the opening thereto and is at its edges of egg-shaped outline.

In the drawing A designates the body of 25 the receptacle; B, the edge surrounding the opening thereto, and C the cover to close said opening.

The receptacle is elongated horizontally and may firmly rest on the feet D. 30

What I claim is—

The design for an ornamental covered receptacle, substantially as shown and described.

Signed at Shelton, Connecticut, this 5th day 35 of March, 1895.

HENRY BERRY.
